UNITED STATES PATENT OFFICE.

EMIL H. PFEIL, OF ANCHORAGE, TERRITORY OF ALASKA.

LINGUAL BAR.

Application filed November 1, 1926. Serial No. 145,618.

My invention relates to improvements in lingual bars as used in dentistry, which consist in the combinations, constructions and arrangements herein described and claimed.

5 An object of the present invention is to provide a lingual bar having a flexible joint intermediate its ends so that the saddles of the dental plate or plates to which the ends of the lingual bar are secured may move 10 or settle in the mouth of the user of the lingual bar as required to conform or fit snugly in the mouth of the user without injury to the mouth of the user.

15 A further object of the invention is the provision of a lingual bar which can be placed in applied position in the mouth of a patient easily and which will remain in place in the mouth of the patient without causing soreness of the gums of the patient.

20 Other objects and advantages of the invention will be apparent from the following description considered in conjunction with the accompanying drawings, in which:—

Figure 1 is a perspective view of the 25 lingual bar with one end thereof attached to the saddle portion of a dental plate, and

Figure 2 is a fragmentary sectional detail view of the joint between the sections of the improved lingual bar.

30 The improved lingual bar is made of any suitable material and conforms substantially in shape with the human jaw, being substantially U-shaped. The lingual bar that the invention provides may comprise two cooperative sections 1 and 2, respectively, each of which is an approximately one-half part of the complete lingual bar. One of such sections, as the section 1, is formed with a socket 3 in one end thereof for the partial reception 35 of a reduced ball head extension 4 on the adjacent end of the other section, a sufficient portion of the ball head 4 being received in the socket 3 to prevent disconnection of the sections from each other. The sections 1 and 40 2 thus will be connected together for universal movement relatively to each other.

45 The outer end portions of the sections 1 and 2 are flattened as indicated at 5 and provide for serrations in the edges thereof, thus 50 producing teeth 6.

55 The outer end portions of the sections 1 and 2 of the lingual bar are adapted to be imbedded or otherwise secured firmly to saddle members as 7 of a partial denture plate or plates having teeth as at 8, thereon.

From the foregoing description of the

various parts of the device the operation thereof will be readily understood. Since the sections of the lingual bar are flexibly connected to each other, the saddles to which the ends of the lingual bar are secured may settle or move relatively to each other in the mouth of a user of the lingual bar and thus may be adjusted as required to fit snugly and comfortably in the mouth of the user, and such relative settling or movements of the saddles in the ends of the lingual bar may take place without any soreness of the mouth of the user being caused by pressure of the lingual bar thereagainst. Moreover, 70 the universal joint between the sections of the lingual bar permits adjustment of the lingual bar quickly and easily in the mouth of the user and tends to obviate soreness of the gums or other portions of the mouth of 75 the user when the lingual bar is in place.

Obviously the invention is susceptible of embodiment in forms other than that which is illustrated in the accompanying drawing, and I therefore consider as my own all such 80 modifications and adaptations as fairly fall within the scope of the appended claims.

I claim:—

1. A lingual bar comprising a plurality of cooperative sections and a universal joint 85 connecting adjacent sections to each other.

2. A lingual bar comprising two cooperative sections flexibly connected to each other at their inner ends, and having their outer end portions adapted to be attached to a 90 dental plate.

3. A lingual bar comprising two cooperative sections, one of said sections having a socket at its inner end and the other section having a ball head extension at its inner 95 end partially received in said socket and cooperating with said socket to flexibly connect said sections together, the outer end portion of each of said sections being adapted to be attached to the saddle portion of a 100 dental plate.

4. A lingual bar comprising two longitudinally curved sections flexibly connected together at their inner ends, the outer end portion of each of said sections being flattened 105 and being provided with teeth in the longitudinal edges of said flattened portion, whereby said outer end portion of the sections is adapted to be secured in place in the saddle portion of a dental plate.

EMIL H. PFEIL.
